CLAIM

The ornamental design for an information console, as shown and described.

DESCRIPTION

FIG. 1 is a front perspective view of the claimed design for an information console;

FIG. 2 is a front view thereof;

FIG. 3 is a right side view thereof;

FIG. 4 is a left side view thereof; and,

FIG. 5 is a top view thereof.

The broken lines immediately adjacent to the shaded area depict boundaries of the claimed design and form no part thereof. The broken lines showing the remainder of the information console depict environmental structure and form no part of the claimed design.

1 Claim, 5 Drawing Sheets

See application file for complete search history.
